UNITED STATES PATENT OFFICE.

GEORGE T. HORTON, OF CHICAGO, ILLINOIS.

GAS HOLDER.

Application filed September 18, 1925. Serial No. 57,084.

This invention relates to improvements in gas holders and more especially to such a device adapted for use in storing relatively large quantities of gas. My improved gas holder may take the place of the telescoping water-sealed gas holders now commonly used by gas companies.

My improved gas holder has no moving parts and is not, therefore, an operating machine. It can be used in practically any case where gas is utilized under pressure. Its use offers a most practicable solution to the problems of heating seals and the discoloration of paint by immersion in water.

15 No water seals are necessary and no part of the holder is telescoped into water.

My improved storage gas holder requires smaller foundations than ordinary holders of like capacity; the cost of this item being 20 cut approximately in half.

The simple, smooth surface of my improved gas holder is easier to paint and contains so much less surface per unit of capacity than lift holders that it can be painted 25 at a cost of from one fifth to one third the ordinary cost. Besides this, it can be painted attractive colors, which harmonize with the surrounding scenery, without fear of discoloration. In fact, my improved gas 30 holder when properly painted, or landscaped, will be a thing of public interest and an object of beauty. It can also be utilized to attract attention and thus aid publicity.

My improved gas holder can be used advantageously in cold climates because there 35 are no water seals to freeze. Because the water seals do not have to be kept from freezing, a heating system, and the duties of an attendant to take care of the same are 40 dispensed with.

My improved gas holder may be made with a relatively large capacity. For example, the one shown in this application is 45 designed with a diameter of substantially fifty-seven feet.

Other features and advantages of my invention will appear more fully as I proceed with my specification.

In that form of device embodying the features of my invention and shown in the accompanying drawings, Figure 1 is a view in side elevation of a gas holder; Fig. 2 is a top plan view; Fig. 3 is a plan view of the foundations and supporting legs with the gas holder removed; Fig. 4 is a vertical sectional view on an enlarged scale taken

through one of the foundations and supporting legs; and Fig. 5 is a view in side elevation on an enlarged scale of one of the supporting legs.

As shown in the drawings, the gas holder comprises a spherical shell 10 made up of plates 11 properly curved and shaped to form a sphere when fastened together. The plates 11 are here shown as joined at their edges by butt-straps 12 on the outside. Similar straps (not shown) may be provided on the inside if desired. The shell plates are joined to the straps in any suitable manner as by riveting or welding.

The shell 10 is entirely supported by twenty supporting legs set on the concrete piers or foundations 17. The shell has no other support. The circle inside of the foundation posts 17 indicated in Fig. 3 indicates merely a circular depression in the ground beneath the gas holder for the purpose of giving easier access to the under surface thereof. Such a depression is optional.

18 indicates the supporting legs (see Figs. 40 4 and 5). Each of these legs comprises a substantially rectangular piece of sheet metal having its upper edge 18^a bent outwardly at an angle of substantially 45°, and curved to conform to the shape of the outer 45 surface of the shell 10. The edge or flange 18^a is fastened to the shell by means of the rivets 19. The lower edge of the leg 18 is fastened by means of the rivets 20 between the vertical edges 21 of two adjacent angle 50 irons, having their horizontal flanges 22 resting on the post or foundation 17. Each supporting leg 18 is provided with two stiffening members 23 comprising vertically arranged plates set at right angles to the member 18 and secured thereto in any suitable manner, as, for example, by welding. The upper end of the stiffening member 23 is likewise secured to the flange 18^a, and the lower end thereof to the horizontal flange 55 22 of the angle iron on that side.

24 indicates an anchor bolt embedded in the foundation 17 and extending through one of the flanges 22 of one of the angle irons and provided with a nut 25 as shown.

The supporting legs are attached to the shell on a circle having about one-half the diameter of a great circle.

The method of supporting the shell on the supporting legs and the location of their attachment to the shell is an important feature of the invention. In making a gas holder of

this size spherical in shape, many difficulties are encountered in properly supporting it, making it of the proper strength and the like. These difficulties have all been overcome in my improved gas holder. The problems encountered in supporting a gas holder are entirely different from those met in supporting a spherical tank adapted to hold a liquid such as water or oil. In such a tank, it is obvious that the pressure on different points in the tank varies greatly with the difference in head of the liquid contained therein. In a gas holder, however, the weight of the gas is practically negligible. For this reason, and because of other differences in construction between a liquid tank and a gas holder, it has been found that in a gas holder the supporting legs may be located much farther in. For example, they may join the shell on a circle having a diameter of substantially one-half of the diameter of a great circle, or even less. By thus supporting the gas holder, it is held rigid and firm and is not subjected to any undue stresses or strains. Moreover, by bringing the supporting legs in, in this manner, it is obvious that there is a great saving in material since the supporting pieces may be much shorter. The construction is also simpler, and besides this, there is a great saving in the size and number of foundations required. It is obvious also, that very much less ground space is required for the gas holder than if the legs were moved out on a larger circle.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as possible in view of the prior art.

What I claim as new and desire to secure by Letters Patent, is:

1. A gas holder comprising a substantially spherical shell substantially supported by supporting legs resting on foundations and attached at their upper ends to the shell on the line of a circle lying in a horizontal plane and having a diameter substantially one-half of the diameter of a great circle of said shell.

2. A gas holder comprising a substantially spherical shell substantially supported by supporting legs resting on foundations and attached at their upper ends to the shell on the line of a circle lying in a horizontal plane and having a diameter substantially one-half of the diameter of a great circle of said shell, each of said supporting legs comprising a piece of sheet metal having its upper edge bent to form a flange, said flange

being curved to conform to the curvature of the shell and attached thereto.

3. A gas holder comprising a substantially spherical shell substantially supported by supporting legs resting on foundations and attached at their upper ends to the shell on the line of a circle lying in a horizontal plane and having a diameter substantially one-half of the diameter of a great circle of said shell, each of said supporting legs comprising a piece of sheet metal having its upper edge bent to form a flange, said flange being curved to conform to the curvature of the shell and attached thereto, and having a stiffening member fastened to said piece of sheet metal and said flange and lying in a plane substantially at right angles thereto. 75

4. A gas holder comprising a substantially spherical shell substantially supported by supporting legs resting on foundations and attached at their upper ends to the shell on the line of a circle lying in a horizontal plane and having a diameter substantially one-half of the diameter of a great circle of said shell, each of said supporting legs comprising a piece of sheet metal having its upper edge bent outwardly to form a flange, said flange being curved to conform to the curvature of the shell and attached thereto. 80

5. A gas holder comprising a substantially spherical shell substantially supported by supporting legs resting on foundations and attached at their upper ends to the shell on the line of a circle lying in a horizontal plane and having a diameter substantially less than the diameter of a great circle of said shell. 90

6. A gas holder comprising a substantially spherical shell substantially supported by supporting legs resting on foundations and attached at their upper ends to the shell on the line of a circle lying in a horizontal plane and having a diameter substantially less than the diameter of a great circle of said shell, each of said supporting legs comprising a piece of sheet metal having its upper edge bent to form a flange, said flange being curved to conform to the curvature of the shell and attached thereto, the lower edge of said piece of sheet metal being supported between the vertical flanges of two adjacent angle irons resting on said foundation. 105

7. A gas holder comprising a substantially spherical shell substantially supported by supporting legs resting on foundations and attached at their upper ends to the shell on the line of a circle lying in a horizontal plane and having a diameter substantially less than the diameter of a great circle of said shell, each of said supporting legs comprising a piece of sheet metal having its upper edge bent to form a flange, said flange being curved to conform to the curvature of the shell and attached thereto, and having a 110

120

125

130

stiffening member fastened to said piece of sheet metal and said flange and lying in a plane substantially at right angles thereto, the lower edge of said piece of sheet metal 5 being supported between the vertical flanges of two adjacent angle irons resting on said foundation.

8. A gas holder comprising a substantially spherical shell substantially supported by 10 supporting legs resting on foundations and attached at their upper ends to the shell on

the line of a circle lying in a horizontal plane and having a diameter substantially less than the diameter of a great circle of said shell, each of said supporting legs comprising a piece of sheet metal having its upper edge bent outwardly to form a flange, said flange being curved to conform to the curvature of the shell and attached thereto. 15

In testimony whereof I have hereunto set 20 my hand this 16th day of September, 1925.

GEORGE T. HORTON.
